United States Patent Office

Des. 212,150

Patented Sept. 3, 1963

212,150

COLLAPSIBLE TUBELIKE CONTAINER

Monte C. Caliman, Jr., Livingston, N.J., assignor to Unette Corporation, Livingston, N.J., a corporation of Delaware

Filed Jan. 2, 1968, Ser. No. 10,024

Term of patent 14 years

(Cl. D9—194)

FIG. 1

I claim:

The ornamental design for a collapsible tubelike container, as shown.
